UNITED STATES PATENT OFFICE

HUBERT ESSER, OF MARSHFIELD, WISCONSIN

TRUSS

Application filed January 3, 1930. Serial No. 418,302.

This invention relates to trusses of the type for use by people suffering with rupture or hernia and has, for one of its objects, to provide a device of this character which may be expeditiously and adjustably secured in position upon the body of the wearer and be worn with a minimum of discomfort.

Another important object of the invention resides in the provision of a pad of a novel construction which will perform its function in a manner to provide maximum relief to the wearer when the same is adjusted in position.

Other objects of the invention are to provide, in a manner as hereinafter set forth, a truss of the aforementioned character which will be simple in construction, strong, durable, efficient in its use and which may be manufactured at low cost.

The foregoing and still further objects and advantages of the invention will become apparent from a study of the following specification, taken in connection with the accompanying drawings wherein like characters of reference designate corresponding parts throughout the several views, and wherein:

Figure 1 is a perspective view of a truss constructed in accordance with this invention.

Figure 2 is a front elevation of the pad, the same being shown mounted on the supporting straps.

Figure 3 is a view in horizontal cross section taken substantially on the line 3—3 of Figure 2.

Referring to the drawings in detail, the reference character 1 designates generally the pad which comprises a rubber body portion 2 which is substantially H-shaped in horizontal cross-section, the end portions 3 of which are connected by the web portion 4. The body portion 2 is formed of pliable rubber. A pair of lips or extensions 5 extend inwardly in spaced relation to the web portion 4 on the inner sides of the end portions 3 and mounted between said end portions and disposed against said lips is a wad of soft material 6, preferably cotton. The wad of cotton 6 is detachably maintained in position through

the medium of the elastic band 7 as most clearly illustrated in Figure 1. Strips of felt 8 are secured to the outer side of the end portions 3 of the body 1 of the pad by the stitching 9. A felt block 10 is secured by any suitable means, such as an adhesive, through the lower end of the rubber body portion 2, as best illustrated in Figure 2 of the drawings.

For the purpose of securing the pad 1 in position, an elastic body encircling adjustable belt 11 is provided which extends transversely across the front side of said pad 1 and is secured thereto through the medium of the loop 12 which encircles the web portion 4 of the pad and said belt 11 and is secured to the forward end of the crotch straps 13. As best illustrated in Figure 3 the loop 12 is of a size to draw the adjacent portion of the belt into the depression formed in the forward side 70 of the pad 1 by the end portion 3 of the body 2. The rear end of the crotch strap 13 is adjustably secured to the rear portion of the belt 11 by the loops 14. The belt 11 is provided with a lining of soft material 15 to prevent chafing of the wearer's body and said lining is slidably secured in position on the inner side of said belt in a manner to permit independent stretching thereof through the medium of the loops 16.

In the use of the truss, the pad is properly positioned against the wearer's body and is secured against displacement by the belt 11 and crotch straps 13 in an obvious manner. When the belt 11 is tightened, the pressure thereof on the opposite side of the loops 12 will force the outer end of the portion 3 of the rubber block 3 outwardly, and the inner end of said portion will be swung toward each other in a manner to yieldingly embrace the injured portion of the body. The felt strip 8 on the outer side of the end portions 3 and the felt block 10 on the lower end of the pad protect the body of the wearer against the comparatively sharp corner portions of the rubber body portion 2, as will be apparent.

It is believed that the many advantages of a truss constructed in accordance with this invention will be readily understood, and al-

though the preferred embodiment of the invention is as illustrated and described, it is to be understood that changes in the details of construction may be had which will fall within the scope of the invention as claimed.

What is claimed is:—

1. A truss of the character described comprising a resilient block of substantially H-shaped horizontal cross section providing a pair of end portions and a comparatively thin connecting web portion, an adjustable body encircling supporting belt extending across the forward side of the block and means for connecting the block to the adjacent portion of the belt in a manner to draw said belt inwardly toward the web portion, said belt adapted to swing the end portions of the block in a vertical plane when tightened.
2. A truss of the character described comprising a resilient block of substantially H-shaped horizontal cross section providing a pair of end portions and a comparatively thin connecting web portion, an adjustable body encircling supporting belt extending transversely across the forward side of the block and a flexible loop encircling the web portion of the block and the adjacent portion of the belt for mounting said block on said belt in a manner to draw the latter inwardly toward the web portions, the portion of the belt on the opposite side of the loop adapted to engage the adjacent side of the end portion of the resilient block in a manner to swing said end portion in a vertical plane when the belt is tightened.
3. A truss of the character described comprising a resilient block of substantially H-shaped horizontal cross section providing a pair of end portions and a comparatively thin connecting web portion, an adjustable body encircling supporting belt extending transversely across the forward side of the block, a flexible loop encircling the web portion and the adjacent portion of the belt for connecting the resilient block and the belt together in a manner to draw said belt inwardly toward the web portion, the portions of the belt adjacent the opposite side of the loop being adapted for engagement with the adjacent side of the end portion for swinging said end portion in a horizontal plane when the belt is tightened, a crotch strap having its forward end secured to the loop and its rear end adjustably coupled to the belt.
4. A truss of the character described comprising a resilient block of substantially H-shaped horizontal cross section providing a pair of end portions and a comparatively thin connecting web portion, an adjustable body encircling supporting belt extending transversely across the forward side of the block, a flexible loop encircling the web portion and the adjacent portion of the belt for connecting the resilient block and the belt together in a manner to draw said belt in-

wardly toward the web portion, the portions of the belt adjacent the opposite side of the loop being adapted for engagement with the adjacent side of the end portion for swinging said end portion in a horizontal plane when the belt is tightened, a crotch strap having its forward end secured to the loop and its rear end adjustably coupled to the belt, and a body of pliant material detachably mounted between the end portion of the block on the rear side of the connecting web portion.

5. A truss of the character described comprising a resilient block of substantially H-shaped horizontal cross section providing a pair of end portions and a comparatively thin connecting web portion, an adjustable body encircling supporting belt extending transversely across the forward side of the block, a flexible loop encircling the web portion and the adjacent portion of the belt for connecting the resilient block and the belt together in a manner to draw said belt inwardly toward the web portion, the portions of the belt adjacent the opposite side of the loop being adapted for engagement with the adjacent side of the end portion for swinging said end portion in a horizontal plane when the belt is tightened, a crotch strap having its forward end secured to the loop and its rear end adjustably coupled to the belt, and a body of pliant material detachably mounted between the end portion of the block on the rear side of the connecting web portion, and resilient pads secured to the outer vertical side of the block and to the lower end thereof.

In testimony whereof I affix my signature.
HUBERT ESSER.
